RESETTER FOR COUNTERS

Woodford A. Kennedy and Eugene Roy
Carpenter, Charlotte, N. C.

Application April 6, 1939, Serial No. 266,288

3 Claims. (Cl. 235—144)

This invention relates to a counting mechanism for registering the number of operations of various machines. The herein disclosed counting mechanism is especially adapted to operate upon a loom to determine the number of picks made by the loom over a given period of time. In many textile mills two or more shifts are often employed, thereby necessitating two or more counting mechanisms for registering separately the picks made by the loom during each shift. These counting mechanisms are driven one at a time from a common shaft and are so arranged that either may be selected, depending upon which shift is operated. Once each day the registered picks are recorded by a mill operator and then it is necessary to reset the counters to zero position.

It is an object of this invention to provide a pick counter for looms and the like comprising a plurality of counting mechanisms with means associated therewith for resetting simultaneously all of said counting mechanisms to zero position in one operation.

It is another object of this invention to provide a counting mechanism of the class described having locking means for rendering inoperative the resetting means while the counting mechanism is in operation. This locking mechanism prevents unauthorized persons from tampering with the counter should an attempt be made to actuate the counter to cause it to give it an improper reading.

Some of the objects of the invention having been stated other objects will appear as the description proceeds when taken in connection with the accompanying drawings, in which—

Figure 1 is an isometric view showing a pick counter with a plurality of registering means associated therewith;

Figure 1A is a view of a key which is used to lock and unlock the re-setting mechanism;

Figure 2 is a front elevation of the parts shown in Figure 1, but omitting the front covers;

Figure 3 is a vertical sectional view taken along the line 3—3 in Figure 2;

Figure 4 is a sectional plan view taken along the line 4—5 in Figure 2;

Figure 5 is an exploded isometric view of a portion of the resetting and locking mechanisms employed in the present invention;

Figure 6 is a detailed view showing the means whereby the resetting shafts pick up the totalizer wheels.

Referring more specifically to the drawings, the numeral 10 denotes a suitable support such

as the arch of a loom to which casings 11 and 12 are secured, said casings having covers 14 and 15 respectively secured to the front side thereof. The cover 14 has transparent windows 16 and 17 therein through which are visible indicating or totalizer wheels 18 and 19 respectively, which are disposed within the casing 11. The upper cover 15 has a transparent window 20 through which is visible the indicating wheels 21 disposed within the casing 12. The wheels 18, 19 and 21 are rotatably mounted on shafts 23, 24 and 25, respectively, in a well known manner. All of these wheels are identical and are adapted to be turned by suitable gears 26, 27 and 28, which gears are adapted to mesh with pinions such as 29 and 30, on longitudinally disposed shafts 31 and 32. These gears 29 and 30 have their teeth notched so as to advance the wheels 18, 19 and 21 in the correct manner upon rotation of the actuating mechanism.

The shafts 23, 24 and 25 have gears 33, 34 and 35 rotatably mounted thereon, said gears being adapted to mesh with worms 36, 37 and 38, respectively. The worms are slidably keyed upon a vertically disposed shaft such as indicated by the reference character 39. This shaft has the fitting 40 fixedly secured around its lower end. Pivoted to the fitting 40 as at 41 is a bar 42, the lower end of said bar having pivoted as at 43 another fitting 44 which is disposed upon the upper end of actuating rod 45 (Figure 1). As this rod turns, rotative movement will be imparted to the gears 33, 34 and 35, which, in turn, will actuate the totalizer wheels 18, 19, and 21 by way of intermediate pinions 29 and 30.

The shaft 39 also has a suitable grooved hub 50 slidably keyed thereon which is engaged by a gear segment 51 on shaft 52 (Figures 2 and 4). This shaft 52 extends through front cover 14 and has a knob 53 secured on its end. The hub 50 has means associated with its upper and lower faces whereby the same may be engaged with worm 36 or 37. This mechanism is more fully shown in co-pending patent application of Woodford A. Kennedy, Serial Number 242,824 filed November 28, 1938.

The shafts 23, 24 and 25 have pinions 55, 56 and 57 fixedly mounted thereon which, in turn, are disposed adjacent the left-hand totalizer wheels 18, 19 and 21, respectively in Figure 2. Disposed between pinions 56 and 57 is an intermediate pinion 58 and this pinion is fixedly mounted around an intermediate shaft 59 the ends of which are journaled in the lower portion of the casing 12. The lower portion of the casing 55

12 and the upper portion of the casing 11 have a suitable slot 60 cut therein through which the lower portion of the pinion 58 is adapted to rotate. This, of course, is necessary in order to cause the pinion 58 to mesh with both the pinion 56 and the pinion 57.

10 The pinions 55, and 56 have disposed therebetween a pinion 61, said pinion 61 being rotatably and slidably mounted on a shaft 62. This shaft 15 has one end thereof rotatably mounted in the end wall of lower casing 11 and its other end rotatably mounted in extension 63, which projects from the back side of the casing (Figures 4 and 5). The shaft 62 extends beyond the exterior of 20 the casing 11, and upon the extending portion is secured a suitable crank 65 which is used when it is desired to reset the counting mechanism, to zero position.

25 The shaft 62 has a suitable collar 66 fixedly secured therearound having a notch 67 in the right hand face thereof (see Figure 2). This notch is adapted to engage a suitable projection 68 which projection is integral with the left hand face of pinion 61. The notches 67 and 68 are normally held in disengaged position as shown in Figure 2, when the counting mechanism is in 30 operation; however, when it is desired to reset the counting mechanism to zero position, a suitable locking means is operated to release the projection 68 together with the pinion 61 to allow it to move to the left into engagement with collar 66 so that the turning of crank 65 will effect a rotation of the intermediate pinion 61 and its associated pinions 55, 56, 57 and 58.

35 The pinion 61 has an annular groove 70 on the right hand side thereof, which groove is adapted to be straddled by the two arms of an L-shaped member 72 forming a slot 71. The extreme right hand end of member 72 (Figures 2, 40 and 5) has a hole 73 cut therein, which hole acts as a cam surface against which projecting cam 74 is adapted to fit. It will be noted by referring to Figures 2 and 5 that the cam 74 is an integral part of a lock cylinder 76 and this lock cylinder is mounted for rotation in a suitable 45 block 78, which, in turn, is secured to extension 63 by any suitable means such as screws 79. The lock cylinder 76 has a key hole 80 therein which is penetrated by a key 81 shown in Figure 1A when it is desired to turn the cam 74 to a different position.

50 The right-hand inside face of the hole 73 is held against the projecting cam member 74 by means of a suitable compression spring 85, said spring being mounted around shaft 62, with one end thereof abutting against the face of pinion 61, and the other end normally abutting against a collar 88 which is slidably and rotatably mounted around shaft 62. The collar 88 is also 55 adapted to have two spaced arms on the right hand end of a U-shaped member 90 fitting against one side thereof. These arms form a slot 89 which passes over the hub of collar 88. The face of member 90 has a slot 91 therein in which the member 72, previously described, is adapted to slide. Since the spring 85 normally tends to expand, it is quite evident that the members 61 and 72 will be biased to the left in Figures 2 and 5 at all times to cause the right hand portion 60 of the hole 73 to contact the cam 74. The expansion of spring 85 will also tend to move member 90 and its associated parts to the right.

65 The right hand end of the member 72 has a slot 75 therein. This slot fits over a projection 75a on block 78. As the cam 74 is turned in one

direction, spring 85 will move member 72 to the left thereby causing the slot 75 to change its position relative to projection 75a.

70 The left-hand end of member 90 has integral therewith laterally and rearwardly extending prongs 93 and 94. These prongs have arcuate cavities 95 and 96 cut therein which are adapted to fit over sleeves 55a and 56a, respectively, extending from pinions 55 and 56 (see Figures 3 and 5). Extending from the right hand face of 10 extensions 93 and 94 are projections 97 and 98 (Figures 2, 3 and 5). These projections are adapted to fit into suitable cavities 99 and 100, cut in the face of pinions 55 and 56, respectively. Due to the tendency of spring 85 to expand, these 15 projections 97 and 98 will normally be forced toward the right and against the left hand face of pinions 55 and 56. When the totalizer wheels 18 and 19 are in zero position the cavities 99 and 100 will be disposed opposite the projections 97 and 98; consequently, the projections will be forced into the cavities to lock the gears or pinions 55 and 56 in position when the cam 74 is rotated to the position shown in Figure 2. Since the lower pinions 55 and 56 are positively geared 20 to the upper pinion 57 through an intermediate gear 58 it naturally follows that shaft 25 for the upper totalizer wheels 21 will also be locked in position when the projections 97 and 98 are disposed in cavities 99 and 100.

25 When it is desired to reset the totalizer wheels 18, 19 and 21 to zero position, the key 81 is inserted in the slot 80 in the lock and the locking cylinder 76 is turned in a counter-clockwise direction in Figures 2 and 5. This will allow the 30 spring 85 to expand and thus cause the pinion 61 together with member 72 to move to the left, because as this lock cylinder is turned in a counter-clockwise direction, the projection 74 will be moved from engagement with the right hand inner face of hole 73. When this operation is 35 effected the projection 68 on the left hand face of pinion 61 will be in an engaging position with the notch 67 which is integral with collar 66 on shaft 22. Upon the turning of the crank 65 in a 40 clockwise manner in Figure 1, the pinions 55, 56 and 57 and 58 are turned to cause the totalizer wheels 18, 19 and 21 to be simultaneously reset to zero position.

45 Figure 6 shows a detailed view of the means whereby the resetting shaft picks up the totalizer wheels. Each of the shafts 23, 24 and 25, has a longitudinally extending groove 105 therein (see Figure 6) and each numeral wheel has a pawl 106, the free end of which is adapted to engage 50 this groove. When the totalizer wheels are operated through the driving mechanism, that is the rod 45, the wheel 18 in Figure 6 will rotate in a counter-clockwise direction. Therefore while rotating in this manner the pawl 106 will move 55 out of the groove 105; however, when it is desired to reset the wheels to zero position the shaft 23 is rotated by means of crank 65 and the gears 61 and 55 in a counter-clockwise manner, and of course when the groove 105 moves into 60 contact with the free end of pawl 106, the totalizer wheel 18 will become an integral part of the shaft, that is when the shaft is rotating in a counter-clockwise manner. A suitable leaf spring 65 107 is employed for normally keeping the free end of the pawl 106 in contact with the periphery of the shaft 23.

65 Members 90 (Figures 2 and 5) have integral therewith projections 90a and these projections are adapted to fit into elongated slots 72a in op- 70

posed edges of member 72. The slots 72a are considerably longer than the projections 90a; therefore, a limited amount of relative longitudinal movement can take place between members 72 and 90. In other words, the projections and slots limit the relative movement between the parts 72 and 90.

It should be borne in mind that when the key 81 is inserted within the lock and the cylinder 10 is turned in a counter-clockwise manner, the member 90 and its associated projections 93 and 94 move to the left, thereby causing the projections 97 and 98 to move out of the cavities 99 and 100 in pinions 55 and 56, respectively. This 15 effects an unlocking of the pinions so that upon the rotation of the crank 65 in a clockwise manner the totalizer wheels can be reset simultaneously to zero position.

In order to prevent unauthorized persons from 20 backing up the totalizer wheels, a suitable leaf spring lock 109 is provided. The upper end of this leaf spring is adapted to engage the teeth in the lower pinion 55 (see Figures 2 and 3). In other words this spring prevents the pinion 55 25 from rotating in a clockwise manner at any time (Figure 3).

It is therefore seen that a pick counter has been provided having a plurality of counting mechanisms with means for resetting simultaneously all of said counting mechanisms and means for locking said resetting means.

In the drawings and specification, there has been set forth a preferred embodiment of the invention and although specific terms are employed, they are used in a generic and descriptive sense only and not for the purpose of limitation, the scope of the invention being set forth in the appended claims.

We claim:

40 1. A counter having a rotatable shaft, a plurality of counting wheels rotatably mounted on said shaft, a pinion fixed on said shaft, means

for locking the pinion against rotation, a driving pinion in engagement with said first-named pinion for rotating said shaft to reset the counting wheels thereon, driving means normally out of engagement with the driving pinion, means for moving the locking means out of engagement with the first-named pinion and moving the driving pinion into engagement with the driving means.

2. In a resetting mechanism for a counter, a 10 rotatable shaft having a plurality of counting wheels rotatably mounted thereon, a pinion fixed on said shaft, a second shaft, a pinion slidably mounted on the second shaft and meshing with the first-named pinion, said second pinion having 15 a clutch face thereon, a rotatable member for driving said second pinion and said rotatable shaft in a resetting direction to reset said counting wheels, resilient means normally pressing the pinion clutch face into engagement with the 20 clutch face on the driving member and key-operated means for moving the second pinion out of engagement with the driving member.

3. In a resetting mechanism for a counter, a 25 rotatable shaft having a plurality of counting wheels rotatably mounted thereon, a pinion fixed on said shaft, a second shaft, a pinion slidably mounted on the second shaft and meshing with the first-named pinion, said second pinion having a 30 clutch face thereon, a rotatable member for driving said second pinion and said rotatable shaft in a resetting direction to reset said counting wheels, resilient means normally pressing the pinion clutch face into engagement with the clutch face on the driving member, key-operated 35 means for moving the second pinion out of engagement with the driving member, and means on the key-operated means for preventing rotation of the first pinion when the clutch faces are held in disengaged position.

WOODFORD A. KENNEDY.
EUGENE ROY CARPENTER.
